UNITED STATES PATENT OFFICE.

MILTON F. DU BOSE, OF DALLAS, TEXAS.

INTERNAL-COMBUSTION ENGINE.

Application filed January 6, 1928. Serial No. 245,014.

This invention relates especially to machines of the double-acting cylinder type and has as its general object to provide an engine of this type which will possess greater efficiency than those now in use.

One of the primary objects of my invention is to eliminate stuffing boxes and the troubles caused by them especially in internal combustion engines.

10 Another object of this invention is to provide a construction which will permit each piston to be continually under power and also to insure that the engine will operate substantially without vibration and without any appreciable noise and in which the power delivered to the power shaft of the engine will be of a constant nature, thereby permitting of an exceptionally flexible control of the speed of operation of the engine, which 20 is a most desirable feature in engines used in automobiles.

Another object of the invention is to provide an engine which will be exceptionally simple in construction and economical to 25 manufacture, and in which the parts are so assembled and constructed that repairs and replacements, when they become necessary, may be effected with a minimum expenditure of time and labor as well as a minimum cost 30 for materials.

Although the drawings in this application represent the applicability of the foregoing to internal combustion engines, the applicability of this mechanism to other uses will be 35 obvious from the accompanying drawings, in which:

Fig. 1 is a perspective of an engine with four cylinders.

Fig. 2 is a perspective of an engine with 40 two opposing cylinders.

Fig. 3 is a section on the line 3—3 of Fig. 2.

Fig. 4 is a side elevation of one of the cylinders with a portion of the casing cut away to show the inside mechanism.

45 Fig. 5 is a front elevation of one of the cylinders with a portion of its casing cut away to show the inside mechanism.

Fig. 6 is a plan view of a cylinder showing the relative position of parts in the head of 50 the cylinder.

Referring to the drawings in detail, I have shown an engine provided with a crank case or base 1, the shape of which will be determined by the number of cylinders and the 55 conditions under which it is to be used. For instance in a stationary engine the cylinder

would be horizontal and the base of very different construction.

Although the cylinders can be cooled by air or water jacketing, it will be noted that in 60 the drawings the engine is shown as water cooled, being provided with the outer wall 2 of the water jacket. As shown in Fig. 3, connecting rods 3 are positioned on each side of the cylinder, which is provided with an 65 exhaust manifold 4. Through pipe 5 compressed air is supplied to the cylinders, each of which is provided with an air intake valve 6 for scavenging air to clean the cylinders of the products of combustion, while the exhaust 70 of the engine is through ports located near the middle of the cylinders. Immediately after the exhaust port is closed, valve 24 opens to admit the combustible mixture of fuel vapor and air, and then the remainder of the 75 return stroke of the piston is the compression stroke. For ignition, a spark plug 9 may be operated by any standard timing device, not shown.

As shown in Fig. 3, the crank shaft 10 of 80 the motor extends through both sides of the crank case 1. To one side the driving mechanism for the air compressor, fuel pump and lubricating pump is attached, while on the other side of the case the flywheel and universal joint or other means for attachment of driven machinery is placed. A piston pin 11, extending all the way through to the outside of the outer walls, serves also as a cross head pin, having a bearing 12 in the trunk 85 piston 13, movable within the outer jacket wall 14, water jacket 15 and inner jacket wall 16, which latter also forms the cylinder wall. Slots 17, formed in the walls of the cylinder, guide the piston pin 11 when reciprocated by 90 the piston 13. The connecting rods 3 are journaled at 18 to blocks 19, which in turn are journaled at 20 to crank shaft 21, provided with three main bearings 22. A flywheel 23 is secured to one end of the crank 100 shaft and is adapted to have a driven belt, mounted thereon, as in the case of a stationary engine.

The combustible mixture is introduced through the intake valve 24 which is operated 105 by a rod 25 formed with extensions 26 and 27 engaging on each side of cam 28, which is so positioned on crank shaft 21 that it will operate the valves when the piston is in the proper position for this operation. An intake 29 for 110 scavenging air introduced through valve 6 receives a supply of air under pressure

through pipe 30, which can be assembled to the motor cast through 4 or cast in unit with 4 or assembled adjacent to 4 for the purpose of heating the air before introducing it into the 5 cylinders. Fuel is supplied through pipe 31 and introduced into the mixing chamber 8 to be mixed with air from pipe 30, while exhaust ports 32 are provided, as heretofore mentioned.

10 Having thus described the invention, what I claim is:

An engine of the double-acting type, comprising a crank case, a plurality of power cylinders, each having its cylindrical walls 15 provided with oppositely disposed slots, a piston slideable in each of said cylinders, a crank shaft extending through opposite sides of said crank case, a piston pin journaled in each piston and extending through opposite 20 sides of said cylinder and guided in said slots

when reciprocated by said piston, a block journaled on said crank shaft adjacent each end thereof, a pair of connecting rods having their outer ends respectively journaled on the outer ends of one of said piston pins and having their inner ends respectively pivoted to said blocks, a second pair of connecting rods having their outer ends respectively journaled on the outer ends of the other of said piston pins, and having their inner ends respectively pivoted to said blocks, inlet and exhaust valves for each of said cylinders, and means for opening and closing said valves, comprising a cam journaled on said crank shaft adapted to be engaged by a rod having contact points positioned on both sides of said cam.

30 In testimony whereof I affix my signature.

35 MILTON F. DU BOSE.
